ALBERT FRANKLIN BROWN, OF LOS ANGELES, AND LAWRENCE BURROUGHS BURCK,
OF PASADENA, CALIFORNIA.

AUTOMATIC MEANS FOR CONTROLLING ELECTRICALLY-HEATED DEVICES.

1,422,735.

Specification of Letters Patent.

Patented July 11, 1922.

Application filed January 16, 1918. Serial No. 212,091.

To all whom it may concern:

Be it known that we, ALBERT FRANKLIN BROWN, a citizen of the United States, residing at Los Angeles, in the county of Los Angeles and States of California, and LAWRENCE BURROUGHS BURCK, a citizen of the United States, residing at Pasadena, in the county of Los Angeles and State of California, have jointly invented an Automatic Means for Controlling Electrically - Heated Devices.

Our invention relates to the automatic control of such heat wherever and in any manner in which it may be used, in any article, machine, or device, using, generating or storing heat generated by electricity, wherein it is desirable or necessary to maintain a uniform temperature of any degree or intensity desired.

We attain these objects by the mechanism illustrated in the accompanying drawings, in which our invention is applied to an ordinary electric flat iron, in which drawings "Fig. 1" is a vertical section of an iron showing our device attached to same; "Fig. 2" is an end view of the same iron showing our device attached as appears from the exterior; "Fig. 3" is a horizontal section showing our device as applied to a flat iron, a portion of the casting being broken away, and Fig. 4 is a detail view, chiefly in vertical section, showing the mounting of the contact elements.

In carrying out the invention, we employ a body portion or casing 10, which is connected in any suitable manner with the handle 12 of usual construction. The heavy base portion is designated 14, and is provided with a chamber 15 in which is mounted a bar 16 of aluminum or other suitable metal, this bar being secured in position by a screw 17. The opposite end of the bar is connected by means of a screw 18 with a block 19, this element 19 serving to mount an adjustable contact member or screw 20, insulated from element 19.

Within the casing 10 is a body portion 23 of metal constituting a heating unit, and below the latter is the resistance element 25

mounted between strips 26 and 27 of mica, 50 or the like. A heavy insulating strip 28 is mounted on the inner wall of the rear end of the casing, and another similar strip 30 is mounted opposite the strip 28 on the outside of the casing—a threaded pin or screw 55 31 passing through the casing and through members 28 and 30 and carrying nuts 32 and 33 on the opposite ends thereof.

In electrical connection with the outer end of pin 31 is a conducting plate 35 adapted to 60 have contact with the complementary contact member 20, and to be spaced from said contact member 20 upon the expansion of the bar 16, when the iron has been heated to the required degree. The breaking of the 65 contact of course breaks the circuit for the heating element or resistance.

A conducting strip 38 extends from one end of the heating element to the pin 31 and is in electrical connection therewith, and the 70 other end of this heating element 25 is in electrical connection with conducting strip 39 leading to a terminal member 40 connected with a socket 41 in the usual manner. The pin 31' is in electrical connection by 75 means of a strip 42 with terminal 43 also connected with the socket, and with contact 20.

A platinum point 45 is carried by contact 20, and a similar point 46 is carried by contact element 35, the latter being of resilient material.

As stated, the application of our device is here shown as applied to an ordinary electric flat iron, but it may be used in any other 85 electric heating apparatus by inserting the aluminum expansion bar into the part of the electric apparatus which is heated, the controlling device being the same as set forth.

We are aware that the expansion and contraction of aluminum or other metal has been previously used in electric thermostat devices. We therefore do not claim exclusive discovery of that principle, but

We claim.

The combination with a body to be maintained at a substantially uniform temperature, of an expansion bar mounted therein,

an adjustable contact element carried by the bar, and a resilient contact element with reference to which the adjustable contact element is movable upon the expansion and contraction of the bar, the contacts maintaining the circuit during the expansion and contraction of the bar to a given degree and

breaking the circuit upon further expansion.
